UNITED STATES PATENT OFFICE.

JAMES BLAKE SCOTT, OF CLEARFIELD, PENNSYLVANIA.

CIRCULATING SYSTEM FOR BOILERS.

1,111,766.

Specification of Letters Patent. Patented Sept. 29, 1914.

Application filed March 29, 1913. Serial No. 757,630.

To all whom it may concern:

Be it known that I, JAMES B. SCOTT, a citizen of the United States, residing at Clearfield, in the county of Clearfield and 5 State of Pennsylvania, have invented certain new and useful Improvements in Circulating Systems for Boilers, of which the following is a specification.

This invention relates to new and useful 10 improvements in boiler construction and more particularly to an improved circulating system therefor, and the primary object of the invention is to provide an improved circulating system which will be a fuel 15 economizer.

A further object of the invention resides in providing improved means for conducting the cool water at the forward end of the boiler to points in direct contact with the 20 fire box and to continue the circulation so mentioned.

Still another object resides in the provision of a ring or the like disposed in the water leg of a boiler, to which are connected 25 water conduits leading from the forward end of the boiler proper.

A still further object resides in so designing this ring as to form a substantial wall in the length of the water leg, said ring being 30 notched on its inner peripheral edge to provide substantial circulating ports between said ring and the walls of the water leg.

A still further object resides in providing 35 a device which is simple and durable in construction, inexpensive to manufacture, and one which is very efficient and useful in operation.

With these and other objects in view, my 40 invention consists in the novel features of construction, combination, and arrangement of parts, as will be hereinafter referred to and more particularly pointed out in the specification and claims.

45 In the accompanying drawings forming a part of this application, Figure 1 is a vertical longitudinal section through a boiler, showing in full lines, my device applied to use therein, Fig. 2 is a fragmentary vertical section through the water leg and ring therein, Fig. 3 is a fragmentary plan view of the rear end of the boiler, with my improved device applied to use, Fig. 4 is a vertical transverse section as seen on line 50 4—4 of Fig. 1, and, Fig. 5 is a fragmentary

vertical section through the water leg of the boiler, showing a slightly modified form of the invention embodied therein.

In describing the invention I shall refer to the drawings, in which similar reference 60 characters designate like parts throughout the several views, and in which 1 designates the outer shell or casing of a boiler of the usual or any preferred type, I having shown in the drawing, a boiler of the well known 65 Vanderbilt type. The fire box 2 at the rear end of the boiler is surrounded by the usual water leg 3, and extending longitudinally through said boiler from the fire box to the forward end thereof, are the usual fire tubes 70 4. It is a well known fact that in boilers of this type, considerable difficulty has been experienced in the heating of the water at the forward end of the boiler and causing a constant circulation thereof through said 75 boiler, and my invention contemplates a means for efficiently and readily accomplishing this result which will, at the same time, lessen the expenditure for fuel. To this end I provide a substantial annulus or 80 ring member 5 which is hollow in design and fits snugly between the walls of the water leg adjacent its lower end. This annulus or hollow ring member is secured in position by means of bolts 6 which extend 85 completely through said ring member and are engaged with the inner and outer walls of said water leg, it being understood of course that the inner wall of the water leg forms the wall of the fire box. This substantial ring member or annulus 5 forms 90 substantially a wall in the length of the water leg, but the inner peripheral edge of the same between the bolts 6 is notched throughout, as shown at 7, to form what may be 95 termed circulating ports, the purpose of which will be hereinafter and more particularly described. In being notched, the ring is provided with openings whereby the contents of the ring will find an exit to the 100 water leg and this construction will be more fully described hereinafter.

Fitted into the top of the ring at the forward end thereof and adjacent the outer edge of the same, are a plurality of stand 105 pipes 8 which extend parallel to the inner and outer walls of the water leg, it being understood that the latter is disposed at an obtuse angle downwardly from the horizontal plane of the boiler proper. These stand 110

pipes alternate with the bolts 6 in the forward end of the ring member 5 and are engaged with additional vertical pipe sections 8, but if desired, these pipes 8 may be continued upwardly and bent in substantial vertical position to extend upwardly into the boiler proper, the former being preferred, as the pipes 9 are arranged throughout the width of the boiler, the same, when extended 10 up into the boiler proper, are of varied lengths, the same being so arranged as to form a substantial semi-circle, as clearly shown in Fig. 4 of the drawings, and engaged with the upper ends of these vertical 15 stand pipes 9 are a plurality of horizontal pipes or conduits 10 which extend longitudinally through the boiler and terminate in a plane adjacent the forward end of said boiler. As shown, the inner or rear ends of 20 the longitudinal pipes 10 are connected to the ends of the vertical stand pipes 9 by means of elbows or unions, but if desired, the stand pipes may be formed from continuations of the longitudinal pipes, the 25 former being preferred.

In operation, it will be appreciated that the water in the water leg surrounding the fire box 2 will be the first to become heated and as the same reaches a pre-determined 30 temperature, the same rises to the surface of the water in the boiler, portions thereof being liberated into steam and passing to the steam dome. As the heated water in the water leg 3 rises, a partial vacuum is formed 35 below the ring member 5, drawing the cooler water therein upwardly and, obviously, as this water is drawn upwardly, a suction will be caused through the ring member, stand pipes and longitudinal pipes. As this suction 40 occurs, the cooler water at the forward end of the boiler will be conducted through the longitudinal or intake pipes 10, downwardly through the stand pipes 9 and 8, into the ring member 5. This water then 45 passes into the water leg through the circulating ports 7, coming in direct contact with the wall of the fire box. As this water is heated through the medium of its contact with the fire box, the same is likewise 50 caused to rise to the surface and, obviously, a constant circulation of the water occurs. The steam is therefore more evenly formed than would be true under ordinary conditions and as the water throughout the boiler 55 will be constantly drawn in circulation and heated, less fuel will be required than is necessary under present conditions.

In the drawings I have shown a boiler of the type well known as the Vanderbilt boiler, wherein the lower portion of the fire box is disposed in a plane below the plane of the lower portion of the boiler proper, but it will be understood that this system of circulation is equally well adapted for 60 use in connection with boilers of other types,

wherein the fire box is in a straight line with the boiler proper.

In Fig. 5 I have shown a slightly modified form of invention, wherein a ring member or band 5' is provided, the same being 70 solid and secured snugly between the inner and outer walls of the water leg by means of the bolts 6'. This band or ring member 5' forms a substantial partition wall in the water leg of the boiler and in order to allow a circulation of water between the inner wall of the water leg and this band, or ring member, the notches 7' are provided on the inner periphery of the same between the bolts 6' to provide circulating ports therein. 80 These ports are identical to the ports 7 in the above referred to form and extending through the forward portion of the ring to points slightly below the same are the stand pipes 8', which lead upwardly and forwardly through the boiler (not shown). The construction of this form of the device is otherwise the same as the form hereabove described and from the description given in connection with the first mentioned form, 90 the operation of this form of the device will be readily understood.

While I have particularly described the elements best adapted to perform the functions set forth, it is obvious that various 95 changes in form, proportion, and in the minor details of construction, may be resorted to without departing from the spirit of or sacrificing any of the principles of the invention.

Having thus described my invention, what I claim is:—

1. In a boiler, the combination with a casing having a fire box therein, a water leg surrounding said fire box, and fire tubes extending from said fire box to the forward end of said casing; of a ring disposed in said water leg, said ring being provided with ports communicating with the water leg, and means to conduct water from the forward end of said boiler to said ring.

2. In a boiler, the combination with a casing having a fire box in the rear end thereof, a water leg formed in the casing surrounding said fire box, and fire tubes extending from said fire box to the forward end of said casing; of a hollow ring disposed in said water leg and having communication with the latter, and a plurality of conduits extending from a point adjacent the forward end of said boiler and having communication with the forward end of said ring.

3. In a boiler, the combination with a casing having a fire box formed in the rear end thereof, a water leg formed in the casing surrounding said fire box, and fire tubes extending from the fire box to the forward end of the casing; of a hollow ring member secured in said water leg adjacent the lower end thereof, said ring fitting snugly between

the inner and outer walls of said water leg, the inner periphery of said ring being notched to provide substantial ports in the water leg and also forming a communication between the ring and said leg, and means to conduct water from the forward end of said boiler to said ring member.

4. In a boiler, the combination with a casing having a fire box formed in the rear end thereof, a water leg formed in the casing surrounding said fire box, and fire tubes extending from the fire box to the forward end of the casing; of a hollow ring member secured in said water leg adjacent the lower end thereof to provide a substantial wall in the length of the same, the inner periphery of the ring member being notched to provide ports between the portions of the leg above and below said ring member, said notches also providing means for communication between the interior of said ring member and said water leg, and conduits extending from points adjacent the forward end of the boiler and communication with the forward end of the ring member.

5. In a boiler, the combination with a casing having a fire box formed in the rear end thereof, a water leg formed in the casing surrounding said fire box, and fire tubes extending from said fire box to the forward end of the casing; of a hollow ring member secured in the water leg adjacent the lower end of the same to provide a substantial wall

in the length thereof, the inner periphery of said ring member being notched to provide substantial ports between the portions of the leg above and below said ring member, said notched portions of the ring member also providing a means of communication between the interior of the ring member and said water leg, stand pipes mounted in the forward portion of the ring member, and intake pipes extending longitudinally of the boiler from a point adjacent the forward end thereof and connected to said stand pipes.

6. In a boiler, the combination with a casing having a fire box therein, a water leg surrounding said fire box, and fire tubes extending from said fire box to the forward end of said casing; of a ring member disposed in the water leg and secured therein to form a substantial partition wall therein, the inner periphery of said ring being notched to provide circulating ports between the same and the inner wall of the water leg, and a plurality of conduits leading from the forward end of said ring to points adjacent the forward end of said boiler.

In testimony whereof I affix my signature in presence of two witnesses.

JAMES BLAKE SCOTT.
